UNITED STATES PATENT OFFICE

HOWARD M. SLOAT, OF FAIRFIELD, CONNECTICUT

MILK BOTTLE CRATE

Application filed July 10, 1928, Serial No. 291,506. Renewed July 28, 1932.

This invention relates to new and useful improvements in milk bottle crates such as are usually constructed of wood and metal and used for holding bottles during transportation, washing and filling. The invention especially refers to a type of crate wherein the sides and end portions are made of wood, constructed to form a crate having closed ends and sides, an open top and an open metal bottom formed of wire rods.

The commercial form of milk bottles crates now to be found upon the market include the above described wood and wire structure, having the ends of their bottom wire rods secured to the wood ends of the crate. There are usually six of these longitudinally arranged wire rods whose opposite end portions extend through the thickness of the end boards of the crate and are riveted or headed down upon the outside to hold the rods in position. These six wire rods are preferably arranged to form three pairs, each pair being positioned to support a row of four bottles so that the three pairs or six rods will properly support a dozen bottles in either upright or inverted positions.

Crates of this type are obviously subjected to very severe usage, being thrown into and dragged out of trucks, delivery wagons, etc., and also dragged around on stone and cement floors of dairies, stores and other places, with the result that sooner or later the short end boards of the crate give away and split along the line of the riveted ends of the wire rods leaving the bottom free to drop out and whereupon it becomes useless, notwithstanding the probable fact that the remaining portion of the crate is in good shape.

I have therefore improved upon this type of milk bottle crates by providing an attachable commercial form of metal bottom which is especially adapted for repairing old crates, or can be used as a part of the original construction of new crates.

With these and other objects in view, the invention resides and consists in the construction and novel combination and arrangement of parts hereinafter more fully described, illustrated in the accompanying drawing, and pointed out in the claims here-

to appended, it being understood that various changes in the form, proportion, size, and minor details of construction within the scope of the claims may be resorted to without departure from the spirit, or sacrificing any of the advantages of the invention.

Similar characters of reference denote like or corresponding parts throughout the several figures of the accompanying drawing forming a part of this specification and upon which

Fig. 1 shows a perspective view of a milk bottle crate formed of wood and metal in accordance with my invention;

Fig. 2 is a further perspective view of a similar crate, the improved form of metal bottom being omitted;

Fig. 3 shows a perspective view of my improved form of attachable metal bottom adapted for attachment to the crate shown in Fig. 2; and

Fig. 4 is a detail vertical sectional view through the reinforced lower edge portion of one end of the crate, and attached channel iron, taken on line 4 of Fig. 1.

Referring in detail to the characters of reference marked upon the drawing 5-5 represent the side of the crate which as before suggested are made of wood, usually about one inch thick and otherwise of proper height and length to produce a crate of the required size. 6-6 represent end members of the crate which like the sides are also formed of wood, of proper size and proportions. Openings 7 are formed in these ends to provide handles adjacent the top edge for handling the crate.

8 represents cross wires within the crate forming separators or partitions for the bottles, the ends of the wires being extended through the sides and headed as at 9. The crate is also provided with longitudinal partition wires that extend through the ends of the crate and headed therein, as shown at 10. 11 indicates nails or screws whereby the side members of the crate are secured to the ends of the end members of the crate.

As above suggested, in commercial milk bottle crates now upon the market, usually the bottoms are the first part to give way,

- caused by the ends splitting and freeing the bottoms so as not to be put back. My improved form of bottom therefore is designed as a replacement bottom and adapted to be put into old crates, from which their bottoms have broken away. This is done by first forming a series of notches 12 in the bottom edge portion of the opposite ends 6 to receive the end portions 23 of the rods 13.
- 10 The attachable bottom, see Fig. 3, is formed in part of a pair of sheet metal channel irons 14-14 which may be alike in construction and include a flat surface portion 15 for covering the bottom edge of the end portion of the crates and upwardly disposed parallel spaced apart flanges 16 and 17 that cover the opposite faces of the edge portions of the end members of the crate.
- 15 The end portions of the inner flanges 17 are cut away as at 18 to accommodate that portion of the lower edge of the sides of the crate which are next adjacent to the bottom edge portion of the ends. These two channel irons are arranged in spaced relation to each other and are connected by a series of rods 13, the end portions of which extend through holes 19 of the inner flanges 17, and the extreme end portions are riveted or otherwise secured in holes 20 in the outer flange 16.
- 20 An intermediate supporting strip or bridge 21 is mounted upon the rods 13 and has its ends bent over at a right angle to engage the inner face of the crate, to which it may be secured in any suitable manner, as by means of a screw 22.
- 25 From the foregoing it will be seen that the crate bottom as shown in Fig. 3 can be conveniently applied to the wood portion of the crate shown in Fig. 2 by simply placing the two channel irons over the lower edge portions of the ends of the crate and whereby the end portions 23 of the rods lying between the two flanges 16 and 17 will readily enter the slots 12 of the end board.
- 30 When the parts are positioned in the bottom of the crate as above suggested the same is secured by rivets 24 placed in aligned holes 25 of the flanges 16 and 17 and in a corresponding hole 26 of the ends of the crate.
- 35 There may be any desired number of these holes and rivets, but three being shown in the drawing, for each channel strip. These are obviously positioned above the depth of the slots so as to guard against further splitting of the end boards.
- 40 These bottoms, including the intermediate bridge supporting member, the rods and channels would be manufactured and assembled in a way to permit them to be quickly applied to either new or old crates. If they were to form re-bottoms for old crates the split-out portions of the old crates would necessarily have to be first replaced and slots provided to receive the bottom rods 13, the
- 45 ends of which are obviously riveted to the

channel irons. By this means old milk bottle crates now useless can be re-bottomed at a minimum cost, and thus made, as I believe, better than originally.

Having thus described my invention, what I claim and desire to secure by Letters Patent is:

1. The combination with a milk bottle crate comprising wood sides and end members, two opposite ones of which are provided with slots that extend in from their edge across the width of said members, of an attachable bottom comprising a pair of elongated channel irons each adapted to cover the entire bottom edge portion of the end of a crate including said slots, each of the side flanges of said channel irons having a longitudinal series of holes therethrough that align with those of the other flange, a series of rods having their opposite end portions secured in said aligned holes of the two side flanges of each of the said channel irons in a way to form a rigid support for the said end and in position to enter the slots, a supporting iron mounted upon said rods between the two said channel irons and adapted to be secured to the crate, and means for securing the said channel irons to bottom edge portions of the ends of the crate.

2. The combination with a milk bottle crate comprising wood sides and end members, two opposite ones of which are provided with slots that extend in from their edge and across the width of said members, of an attachable bottom comprising a pair of elongated channel irons each adapted to cover the entire bottom edge portion of the end of a crate including said slots, the inner flange of each channel iron extending from one inside wall to the other and the outer flange extending the full outside width of the crate and each having a longitudinal series of holes therethrough that align with those of the other flange, a series of rods having their opposite end portions secured in said aligned holes of the two side flanges of each of the said channel irons to form a rigid support for the said ends and positioned to align with the slots, a supporting iron mounted upon said rods between the two said channel irons and adapted to be secured to the crate, and means for securing the said channel irons to bottom edge portions of the ends of the crate.

3. The combination with a milk bottle crate comprising wood sides and end members, two opposite ones of which are provided with slots that extend in from their edge and across the width of said members, of an attachable bottom comprising a pair of elongated channel irons each adapted to cover the bottom edge portions of the two said members and their slots, the side flanges of said channel irons being disposed upward to cover both the inner and outer faces of the edge

portion of the crate from corner to corner, and each of the side flanges of said channel irons having a longitudinal series of holes therethrough that align with those of the other flange, a series of rods having their opposite end portions secured in said aligned holes of the two side flanges of each of the said channel irons to form a double bearing for each end of the rods which are aligned to

5 enter the slots, a supporting iron mounted upon said rods between the two said channel irons and adapted to be secured to the crate, and means for securing the said channel irons to the bottom edge portion of the ends of the

10 crate.

4. The combination with a milk bottle crate comprising wood sides and end members, two opposite ones of which are provided with slots that extend in from their edge and

20 across the width of said members, of an attachable bottom, comprising a pair of channel irons each adapted to cover said slots and the entire bottom edge portions of the ends of the crate and including side flanges

25 each having a longitudinal series of holes therein which register with holes in the other flange, a series of rods having their end portions engaged in a hole of each of the spaced apart side flanges to form a rigid support,

30 the end portions of said rods between the two said flanges being positioned and adapted to enter the said slots, and means for attaching the said bottom to the bottom edge portions of the crate.

35 Signed at Bridgeport, in the county of Fairfield and State of Connecticut this 9th day of July, A. D. 1928.
